UNITED STATES PATENT OFFICE.

JESSE R. THOMAS, OF CARTHAGE, MISSOURI, ASSIGNOR TO BARNETTE T. STEINER, OF CANTON, OHIO.

SUPPORTING DEVICE FOR VEHICLE-TOPS.

1,044,427.

Specification of Letters Patent. Patented Nov. 12, 1912.

Application filed April 18, 1912. Serial No. 691,641.

To all whom it may concern:

Be it known that I, JESSE R. THOMAS, a citizen of the United States, residing at Carthage, in the county of Jasper and State 5 of Missouri, have invented new and useful Improvements in Supporting Devices for Vehicle-Tops, of which the following is a specification.

My invention relates to novel and improved means for supporting and maintaining in a collapsed position the bows of the 10 tops for vehicles.

For the purpose of illustration, I have, in the accompanying drawings, shown and 15 herein described one form of device embodying my invention.

Figure 1 is a side elevation of a vehicle, and a supporting device embodying my invention, as applied thereto to support and 20 clamp the bows of its top. Fig. 2 is a side elevation of the supporting device, enlarged, supporting and clamping a set of bows, a portion of the latter being shown in folded 25 position. Fig. 3 is an end elevation of the parts shown in Fig. 2, the bows being shown in cross section.

In the drawings, 1 indicates a vehicle which may be of any suitable or preferred construction.

2 indicates the top thereof supported in a well known manner by sets of bows 2^a that may be folded or collapsed into the position shown in Fig. 1.

3 indicates brackets or arms extending 35 from the opposite sides of the vehicle (only one bracket being shown in the drawings) and fixed thereto in any suitable way. The bracket 3 is preferably round in cross section.

4 indicates a sleeve or collar slidably fitting the bracket 3 and arranged to be adjusted laterally thereon toward and from the vehicle 1 and also rotatably, a set screw 4^a being provided to secure the sleeve or collar 45 in its adjusted position on the bracket 3.

5 indicates a seat, preferably elongated, extending transversely with respect to the sleeve 4. The seat is preferably formed integral with the collar 4. It may be of 50 concave formation to prevent lateral displacement of the lowermost bow 2^a.

At 5^a, the seat 5 may be provided with a protective covering of felt or leather which forms a cushion-like surface and prevents 55 injury to the enamel of the adjacent bow.

6 indicates a pair of reinforcing members preferably comprising L-shaped rods, one arranged on either side of the sleeve 4. As shown, the opposite ends of each rod 6 are secured to the sleeve 4 and seat 5, one arm 6^a of the rod extending horizontally in a direction longitudinally of the seat from the sleeve to a point more or less near the adjacent end of the seat 5. In the preferred form of the invention the rods 6 are formed integrally with the sleeve and seat. 65

7 indicates a strap adapted to tightly clamp the bows 2^a to the seat 5 to overcome relative movement between them and the vehicle 1, especially when the latter is traversing a rough road. One end of the strap 7 is loosely hinged or connected in a well known manner to the horizontal arm of one of the strengthening rods 6. The strap is formed with the usual openings 7^a, any one 75 of which is arranged to engage a pin or stud 9 projecting from the seat 5. From the rod 7 the strap extends up one side of the folded bows and then over the uppermost bow, and down on the opposite side of the bows where it is connected to the stud 9 in the manner illustrated in the drawings. 80 The stud 9 may be bent or inclined downwardly to insure against accidental displacement of the strap. The strap 7 may be 85 made of such length to permit it to be wrapped around the bows one or more times. The stud 9 is preferably arranged on the side of the sleeve 5 opposite to that side to which the strap is pivotally connected. 90 After the strap 7 has engaged the stud 9, its free end may be extended through the opening between the seat and the adjacent rod 6, the latter serving in this manner to 95 maintain the strap in engagement with the stud 9.

To those skilled in the art of making devices of the class described, many alterations in construction and widely differing embodiments and applications of my invention will 100 suggest themselves, without departing from the spirit and scope thereof. My disclosures and the description herein are purely illustrative, and are not intended to be in any sense limiting.

It will be seen from the foregoing description that I have provided a simple form of bow rest and clamping means, the seat member of which is connected directly to 110 and formed integral with a sleeve or collar

that is adjustably mounted at the side of a vehicle, and that the seat or rest extends forwardly and rearwardly from said sleeve and is provided with rods which extend in 5 a direction longitudinally of the seat, and are connected at their opposite ends to the sleeve and seat to reinforce the latter. It will further be seen that one of the reinforcing rods forms a pivotal connection for 10 one end of the bow binding strap, no additional means being required for connecting the strap to the device.

What I claim is:—

15 In a device of the character described, the combination with a bracket arranged at one side of a vehicle, of a collar or sleeve adjustably mounted on said bracket, means for securing the collar or sleeve to the bracket in its adjusted position, a seat mounted on 20 said sleeve and arranged to support the lowermost bow of a set of bows, a reinforcing L-shaped rod arranged at either side of the sleeve and extending between and hav-

ing its opposite ends connected to the sleeve and seat, one arm of each L-shaped rod extending from the sleeve horizontally in a direction longitudinally of the seat to a point near its adjacent free end and the other arm of the rod extending from the seat in a vertical direction, a strap having one 30 end loosely pivoted on one L-shaped rod and arranged to extend over the bows when the latter are folded on said seat, and a stud to which the opposite end of the strap is detachably connected, the said stud being carried by the seat and arranged between the vertical arm of the other L-shaped rod and the sleeve and permitting the free end of the strap to be inserted through the opening between the adjacent L-shaped rod and sleeve 40 and held on said stud.

JESSE R. THOMAS.
